AUTOMATIC STARTER FOR MOTOR VEHICLES

Kenneth R. Blake, Anderson, Ind., assignor of one-fourth to B. D. Emanuel, Anderson, Ind.

Application August 21, 1933, Serial No. 686,169

9 Claims. (Cl. 123—179)

This invention relates to automatic starters for motor vehicles.

The primary object of this invention is to provide an automatic starter adapted to be operated by the accelerator pedal of the motor vehicle during its initial depression which may function only as an accelerator pedal after the engine has been started.

A further object of this invention is to provide an automatic starter of the above mentioned character including a switch arm operated by a pivoted latch held into engagement with the accelerator control rod by electro-magnetic means and moved out of engagement with the accelerator control rod by suction operated means.

A still further object of this invention is to provide an electro-magnet for holding the pivoted latch into engagement with the accelerator control rod operating device adapted to be released upon starting of the motor whereupon the suction operated device becomes operable to trip the pivoted latch from engagement with the accelerator control rod.

25 A still further object of this invention is to provide an automatic starter of the suction operated release type controllable by one of the motor control levers and having means for preventing the operation of the suction release mechanism until the motor has been actually started thereby preventing the objectionable clattering of devices of this type and preventing the opening of the starter motor circuit before the internal combustion engine or motor has been caused 35 to operate by its own power.

A still further object of this invention is to provide an automatic starter for motor vehicles of the above mentioned character arranged so as to be quite effective and at the same time fool 40 proof.

Other objects and advantages of the invention will become apparent during the course of the following description, forming a part of this specification, taken with the drawing and where- 45 in is shown,

A vertical cross sectional view of the device embodying this invention.

In the drawing, wherein for the purpose of illustrating the invention and wherein like reference characters will be employed to designate like parts throughout the same, the reference character 5 will generally be employed to designate a casing preferably tubular in cross section, being closed at the top as at 6 and having a bottom wall as at 7. Formed on the lower portion

of the tubular casing 5 is an enlargement 8 to accommodate a portion of the operating mechanism.

Slidably mounted in the upper portion of the tubular casing 5 adjacent the top wall 6 is a slide bar 9 having the opposite ends thereof extending through slots 10 and 11. One end of the slide bar 9 is provided with an opening 12 to which is connected a coil spring 12a that is attached at its other end to an arm 12b for the purpose 60 of establishing a connection between the slide bar 9 and the conventional accelerator operating rod 12c of a motor vehicle.

The casing 5 may be attached by means of suitable brackets or the like to the chassis frame or other part of the motor vehicle under the hood so that the slide bar 9 may extend parallel with the accelerator control rod and may be moved therewith. On the opposite end of the slide bar 9 is formed an internal stop 13 and an external 70 stop 14 for limiting the movement of the slide bar 9. Encircling the slide bar 9 is a coil spring 15 having one end as at 16 abutting the inner wall of the casing 5 while the opposite end is adapted to abut a rigid washer 17 secured to the slide 80 bar 9 in any suitable fashion. Formed on the slide bar adjacent the internal stop 13 is a notch 18 having a cam face 19 and a straight face 20 adapted to engage a latch operator which will be 85 hereinafter more fully described.

Mounted in the lower portion of the housing 5 is a solenoid 21 having a reciprocable armature 22 adapted to be attracted by the pole piece 23 of said electro-magnet or solenoid 21. Connected to the armature 22 is a slide rod 24 having the 90 upper end thereof connected to a crescent shaped latch lever 25 in a pivotal fashion as at 26 so that the free end of the latch lever 25 may engage as at 27 within the notch 18 of the slide bar 9.

Secured to the inner wall of the housing 5 in 95 the upper portion thereof is a bracket 28 held in place by means of a suitable rivet or the like 29 and having an elongated slot 30 through which the latch lever 25 extends for the purpose of guiding said latch lever in alignment with the accelerator operated rod 9. The electro-magnet or solenoid 21 may be held in place by means of a bridge member 31 having angle ends 32 for receiving the inner ends of machine screws 33. An opening is formed as at 34 for receiving the pole 105 piece 23 of the armature.

Secured to the inner wall of the casing 5 above the solenoid 21 is a switch arm 35 by means of a screw threaded bolt 36 as at 37. The screw threaded bolt 36 is insulated from the casing 5 by means 110

- of bakelite washers 37 on opposite sides of the casing wall. The free end of the switch arm 35 is adapted to be return bent as at 38 and is provided with an insulating block 39 adapted to be engaged by a curved portion of the latch lever 25. Formed on the switch arm 35 is a contact 40 adapted to engage a contact 41 secured to the side wall of the casing 5 by means of a nut 42 and insulated by means of bakelite washers 43 positioned on opposite sides of the housing. Directly above the contact 40 on the switch arm 35 is a similar contact 44 adapted to engage a stationary contact 45 secured to the side wall of the casing and held in place by nuts 46 and insulated from the casing by suitable insulating washers 47. It will be noted that the switch arm 35 is so positioned as to be engaged by the latch lever 25 to move said switch arm 35 into engagement with the contacts 41 and 45 consecutively.
- 20 The lower end of the solenoid armature 22 extends through an opening in the bottom wall 7 of the casing and into the diaphragm chamber 49 comprising an upper cup-shaped element 50 and a lower cup-shaped element 51 secured together by a return flange 52 extending over an annular flange 53 formed on the lower cup-shaped element 51. Interposed between the connections 52 and 53 is a diaphragm 54 forming a vacuum chamber 55 there below. The upper element 50 is connected to the bottom wall 7 of the casing by means of suitable rivets 56 provided with an opening 57 for allowing the free movement of the solenoid armature 22. Extending through the diaphragm 54 is a screw 58 anchored in the lower end of the solenoid armature 22 so that the armature and diaphragm 54 will move in unison.
- 25 A flexible pipe may be connected to the screw threaded boss 59 formed centrally on the lower cup-shaped element 51 so that the opposite end thereof may be connected to the intake manifold of the motor vehicle whereupon suction created by the operation of the engine will create suction in the chamber 55 and cause the movement 30 of the diaphragm 54 in a downward direction.
- 30 It is intended to connect one terminal of the usual motor vehicle storage battery to the switch arm anchoring post 36 so that current may flow through the switch arm 35 and through the contacts 40 and 41 when the switch arm 35 is in its closed position so that the lead lines 60 establish electrical communication between the storage battery and the solenoid 22 while the lead line 61 may be connected to the opposite end of the 35 solenoid 21 to a binding post 62 suitably insulated from the casing 5 by bakelite washers 64. The binding post 62 may be connected to the generator of the motor vehicle by means of a suitable lead line (not shown).
- 40 The terminal of the starter motor solenoid may be connected to the binding post or contact 45 so that after the contacts 40 and 41 have engaged by reason of the movement of the slide bar 9 carrying the latch lever 25 into engagement with the switch arm 35, the contacts 44 and 45 may be engaged thereby closing a suitable circuit through the storage battery, starter motor solenoid and returned through a suitable ground connection whereupon starting of the 45 engine occurs and operates the generator of the motor vehicle producing current to oppose the storage battery current and neutralize the solenoid 21. Upon neutralization of the solenoid 21, the suction created by the internal combustion 50 engine in the intake manifold will create suction

in the chamber 55 thereby drawing downwardly upon the diaphragm 54 and causing the pivoted latch lever 25 to move out of engagement with the notch 18 of the slide bar 9. This movement allows the complete movement of the slide bar 9 relative to the latch lever 25 without affecting the same or without having any effect upon the switches including the contacts 40, 41, 44 and 45. A stop 66 may be provided in the housing 5 for engaging the latch lever 25 and guiding the same in its up and down movement while at the same time holding it into engagement with the insulating block 39 thereby preventing vibration of the arm 35 to an undue extent.

55 For a consideration of the operation of the device, it will be assumed that the slide bar 9 and latch lever 25 are in their respective positions, also the switch contacts 40, 41, 44 and 45. These positions are maintained when the motor vehicle upon which the device is attached is parked or at a standstill without the engine running. It will be assumed that the operator of the motor vehicle desires to start the engine of the motor vehicle whereupon he depresses the usual accelerator foot pedal which causes 60 the movement of the slide bar 9 toward the right against the tension of the coil spring 15. Such movement causes the travel of the latch lever 25 in the same direction whereupon the latch lever 25 will engage the free end 38 of the switch arm 35 to cause the contact 40 to engage the contact 41. Immediately an electrical connection is established between the storage battery of the motor vehicle and the solenoid 21 which energizes the solenoid and retains the armature 22 in the 65 position shown in the drawing by reason of the fact that the armature 22 is attracted by the pole piece 23 and held in its most upwardly position thereby holding the latch lever 25 so that the free end 27 will engage the notch 18 during 70 the continuous travel of the slide bar 9.

75 Upon continued movement of the slide bar 9 said latch lever 25 causes the contacts 44 and 45 to close which immediately establishes electrical connection between the storage battery of 80 the motor vehicle and the starter solenoid which causes the energization of the electric starter and the resultant starting of the internal combustion engine.

85 After the engine has been started, the generator thereof produces sufficient current to neutralize the current passing through the solenoid 21 which releases the armature 22 and allows the free movement thereof. Also upon starting of the internal combustion engine, suction is created in the intake manifold which is connected through the vacuum chamber 55 thereby lowering the diaphragm 54 against the action of a coil spring 67 which moves the pivoted latch lever 25 downwardly along with the armature 22 and connecting rod 24 so that the free end of the pivoted latch lever 25 will move out of engagement with the notch 18.

90 After the free end 27 of the pivoted latch lever 25 has moved out of engagement with the slide bar notch 18, the slide bar 9 may be moved freely without engaging the same for the purpose of accelerating the internal combustion engine and as long as the internal combustion engine is under its own power the switches including contacts 40, 41, 44 and 45 will remain open but immediately upon stalling of the internal combustion engine the coil spring 67 will move the armature 22 upwardly so that the free end 27 of the pivoted latch lever 25 will engage 95

the slide bar 9 and the engine may be re-started by depressing the accelerator pedal as before mentioned.

I claim:—

5 1. An automatic starter control for motor vehicles comprising a slide bar, a latch lever adapted to engage the slide bar, an electro solenoid for holding the latch lever in a raised position, an electric switch adapted to be closed by 10 the latch lever and a vacuum operated dia- phragm for moving the latch lever downwardly.

15 2. An automatic starter control for motor vehicles comprising a slide bar adapted to be operated by one of the motor vehicle controls, a solenoid having an armature operated thereby, a pivoted latch lever secured to the armature adapted to be held by the solenoid in engagement with the slide bar, electric switches mounted in the path of the pivoted latch lever and suc- 20 tion operated means for moving the latch lever out of engagement with the slide bar.

25 3. An automatic starter control for motor vehicles comprising a slide bar having a notch and adapted to be operated by one of the motor vehicle controls, a solenoid having an armature, a pivoted latch bar secured to the armature and adapted to have its free end engage in said slide bar notch, a switch arm in the path of the pivoted latch lever, and vacuum operated means for tri- 30 ping the pivoted latch lever.

35 4. An automatic starter control for motor vehicles comprising a casing adapted to be mounted thereon, a slide bar mounted in the upper end of the casing, adapted to be operated by one of the motor controls, a solenoid mounted in the lower portion of the casing, a pivoted latch lever adapted to be held in engagement with the slide bar, two sets of electric contacts mounted in the path of the pivoted latch lever, and means 40 for moving the latch lever out of engagement with the slide bar after one of the sets of contacts has been engaged.

45 5. An automatic starter control comprising a casing, a slide bar having a notch in the upper end of the casing, a solenoid mounted in the lower end of the casing, a latch lever pivoted to the armature of the solenoid, a switch arm mounted in the path of the pivoted latch lever, a pair of contacts carried by the switch arm, a 50 pair of stationary contacts to be engaged there- by in successive order, one of said switches being employed in the starter motor circuit, the other set being in circuit with the solenoid, and suction operated means for moving the pivoted latch

lever out of engagement with the slide bar, after the solenoid has been de-energized.

6. In an automatic starter control for motor vehicles, a shiftable member adapted to be operated by one of the motor vehicle controls, a latch lever adapted to engage the shiftable member, electro-magnetic means for retaining said latch lever in its engaged position, a starter switch and electro-magnet switch mounted in the path of the latch lever to be operated successively and suction operated means for moving the latch lever out of engagement with the shiftable member after the engine has started.

85 7. In an automatic starter control for motor vehicles, a shiftable member adapted to be operated by one of the motor vehicle controls, a latch lever adapted to engage with said shiftable member, electro-magnetic means for holding the latch lever in engagement with said shiftable member, means operable by the latch lever for closing the starter motor contacts, means also operable by the latch lever for closing solenoid contacts, engine operated means for de-energizing the solenoid and suction operated means for moving the latch lever out of engagement with the shiftable member whereby said shiftable member may be free to move without affecting the starter control switch.

90 8. In an automatic starter control for motor vehicles, a shiftable member adapted to be operated by an accelerator operating device, starter motor contacts, means operable by the shiftable member for engaging the starter motor contacts, electro magnetic means for holding said first mentioned means in engagement with said shiftable member and suction operated means for moving it out of engagement with said shiftable member whereby the shiftable member may function independently of the first mentioned means.

100 9. In an automatic starter control for motor vehicles, a shiftable member adapted to be operated by an accelerator operating device, starter motor switch contacts, a switch arm for said contacts, means operable by the shiftable member for closing said contacts, electro-magnetic means for holding the first mentioned means in engagement with the shiftable member, a switch for controlling the electro-magnetic means also operable by the first mentioned means and suc- 110 tion operated means for rendering the first mentioned means inoperative, after the electro-magnetic means has become de-energized.
